Term of patent 14 years

(Cl. D14—3)

FIG. 1.

Des. 198,365

PAGE 2

FIG. 3.

FIG. 1 is a perspective view of the right side and rear portion of a fork lift truck embodying my new design;

FIG. 2 is a perspective view of the front portion and right side thereof; and

FIG. 3 is a perspective view of the rear portion and right side thereof.

The side not shown has substantially the same appearance as the side which is shown, and the dominant features of the design reside in the portions shown in full lines.

I claim:

The ornamental design for a fork lift truck, substantially as shown and described.
